Guy R. Gauntt,

By William L. Symons
Kas Attorney

UNITED STATES PATENT OFFICE.

GUY R. GAUNTT, OF ROANOKE, ALABAMA.

DIES FOR FORMING RAIL BRACES.

Application filed August 23, 1922. Serial No. 583,693.

To all whom it may concern:

Be it known that I, GUY R. GAUNTT, a citizen of the United States of America, residing at Roanoke, in the county of Randolph and State of Alabama, have invented certain new and useful Improvements in Dies for Forming Rail Braces, of which the following is a specification.

My invention relates to apparatus for manufacturing rail braces.

An object of my invention is the construction of dies and parts co-operating therewith to form rail braces and similar devices by a single operation on the metal of which the braces are made.

A further object of my invention is the construction of dies, one of which is stationary, and one of which is moving, each having as a part thereof suitable tools to completely form a rail brace from a strip of heated metal, and to expel from the forming parts of the dies the completed brace. A further object of my invention is the use of a hammer or upsetting means which acts in conjunction with the dies to form a brace complete in every particular except the holes for attaching the brace to cross ties or other holding means.

With these and further objects in view, one embodiment of my invention is shown in the accompanying drawings in which:—

Figure 1 is a plan view of the dies and hammer, some of the parts being shown in sections;

Figure 2 is a front view of the stationary dies;

Figure 3 is a similar view of the moving die;

Figure 4 is a section on line 4—4 of Fig. 2 as the two dies appear when in closed position;

Figure 5 is a top plan of a completed brace;

Figure 6 is a side view of the brace in position against a T rail shown in dotted line, and

Figure 7 is a plan of a strip of metal from which the braces are struck.

The stationary die 1 is fastened to a bed or tracks by means of bolts 2 or any other suitable means such as rear braces, not shown. The moving die 3 reciprocates on the bed or tracks 4 in a manner well understood and further hereinafter explained.

The stationary die consists of a block 5

in which are recesses to hold two rectangular pieces 6 and 7 which are attached to the die by any suitable means such as bolts 8, each block having three bolts as shown. The front of these rectangular pieces is flush with the front of the die, as clearly shown in Figure 4. Adjacent one end of the block is a recess or an opening 9 in which the punch on the moving die acts. The use of the rectangular pieces enables the size of this recess to be changed to manufacture different sizes of braces. This opening has therein a creasing member 10 which is removably attached in a recess 11 in the block by a screw 12, permitting different sized and shaped members to be inserted. On either side of the creasing member are angle members 13 attached to the block by screws 14 in order to produce the inclined parts of the brace. Different sized and shaped members may be used. In the block are three spring members 15, one of which is shown in Figure 1 in plan, these spring members being adapted by their construction to be pushed by the metal flush with the bottom of the recess. When the pressure of the punch is removed they will operate to expel the completed brace. These springs, and the spring in the punch to be later referred to, operate as described due to their special construction which comprises an opening 15^a through the block having an enlarged end 15^b and another enlarged end 15^c. A nut 15^d is attached to the bolt 15^e by pin 15^f. This bolt has a head 15^g equal in size to the enlarged end 15^c. A coil spring 15^h will act to expel the brace when pressure is removed from the head. Suitable rollers 16 are attached to the rectangular piece 7 to enable the heated strip of metal 17 to be brought in front of the die.

The punch 18 is of the same shape as the socket 9 and is attached to the moving die by bolts 19. In the opening or socket 20 in the punch is an inclined member 21 fastened by screw 22 to the moving block, this member acting to prevent the top of the creased part of the brace from bending away from the top of the creased member. Members of different size and angle may be used. In the socket of the punch is a spring 23 adapted to assist in expelling the complete rail brace if it should become lodged in the opening in the punch. The construction of

this spring is substantially the same as the construction of springs 15. The moving block is operated by lever 24 or by any other suitable means from a source of power not shown in a manner which is well understood in this art.

It will be understood from the drawings that the punch has a suitable clearance, say $\frac{3}{16}$ of an inch, from the cutting edge to the back of the punch.

An upsetting hammer or tool 25 acting in a sleeve 26 through any suitable source of power not shown is timed to act in connection with the die in order to produce the turned back part 27 on the completed brace 28. The action of the upsetting tool on the blank is timed to follow the completion of the action of the moving die on the blank and while the blank is held by the moving and stationary dies; that is the action of the upsetting tool on the blank takes place before the moving die starts back to release the formed blank.

The operation of my device will be clearly understood from the above description and may be briefly stated as follows:

The timing mechanism to bring in proper relations at the proper time the heated metal strip from which the braces are clipped off one at a time by the punch, the traveling die and the upsetting hammer, is not shown as it forms no part of my invention, and is well-known in the art of metal forging.

When a strip of metal properly heated in order to be acted upon efficiently, and of a suitable width, which will be of a width equal to or greater than the longest diameter of the punch, is brought in front of the punch and co-operating parts, the end is first cut in the shape indicated at 29 in Figure 7. The timing mechanism then causes the metal to be moved forward exactly the distance determined by the size of the punch. When it has reached this point, it is acted on by the punch 18, the shape of part 30 being the same shape as the punch 18. As the stroke of the punch is completed, the upsetting hammer 25 acts to produce the completed brace shown in Figure 5, the openings 31 therein being made after the brace is completed. It is obvious that the piece cut from the end 29 of the strip and the pieces 32 made by each cut will be scrap metal.

Having described my invention, what I claim and desire to protect by Letters Patent is:—

1. Dies for forming rail braces comprising a stationary die, said die having brace forming recesses therein and a brace expelling member in said recess, a moving die, an upsetting hammer, and means to bring these parts into operative relation whereby a complete brace may be formed in a single operation.

2. Dies for forming rail braces comprising a stationary die, said die having a brace forming recess therein and a brace expelling member in said recess, a moving die, said die having a punch attached thereto to cooperate with the recess in said stationary die, an up-setting hammer, and means to bring these parts into operative relation whereby a complete brace may be formed in a single operation.

3. In dies for forming rail braces, a stationary die, said die comprising a block having recesses in one side thereof, pieces secured in said recesses, said pieces having a punch receiving recess therein, a creaser in said punch receiving recess and angle members in said punch receiving recess on opposite sides of said creaser.

4. In dies for forming rail braces, a stationary die, said die comprising a block having recesses in one side thereof, pieces removably secured in said recesses, said pieces having a punch receiving recess therein, a removable creaser in said punch receiving recess, and removable angle members in said punch receiving recess on opposite sides of said creaser.

5. In dies for forming rail braces a moving die, said die comprising a block, a punch removably attached to said block having a socket therein, and an inclined member removably attached in said socket.

6. Dies for forming rail braces and similar devices comprising in combination a stationary die having recesses therein provided with a creasing member and angle members, said dies having rollers on the face thereof to carry a brace forming blank, a moving die having a punch attached thereto adapted to act on the brace forming blank in conjunction with the stationary die, said punch having a socket therein and an inclined member attached to said die in said socket and an upsetting hammer adapted to act in conjunction with said stationary die and said moving die to produce a turned back part on a completed brace.

7. Dies for forming rail braces and similar devices comprising in combination a stationary die having recesses therein provided with a creasing member and angle members, and said recesses having a spring member therein, said die having rollers on the face thereof to carry a brace forming blank, a moving die having a punch attached thereto adapted to act on the brace forming blank in conjunction with the stationary die, said punch having a socket therein, and an inclined member attached to said die in said socket and said socket having a spring member therein and an upsetting hammer adapted to act in conjunction with said stationary die and said moving die to produce a turned back part on a completed brace.

8. Dies for forming rail braces and simi-

lar devices comprising in combination a stationary die having recesses in one face thereof, pieces secured in said recess, said pieces having a punch receiving recess therein, a creaser in said punch receiving recess, angle members in said punch receiving recess on opposite sides of said creaser, said die having rollers on the face thereof to carry a brace forming blank and spring members in 5 said punch receiving recess, a moving die having a punch attached thereto adapted to act on the brace forming blank in conjunction with the stationary die, said punch having a socket therein, and an inclined member 10 attached to said die in said socket and said socket having a spring member therein and an upsetting hammer adapted to act in conjunction with said stationary die and said

moving die to produce a turned back part 20 on a completed brace.

9. In a die having an opening therethrough, the end portions of said opening being of greater diameter than the portions intermediate of said end portions, a spring member, said member comprising a bolt, a 25 nut on one end and a head on the other end of said bolt, said nut being of a size to prevent it entering the intermediate part of said opening, a spring surrounding the part of said bolt adjacent the end thereof having a 30 head, said spring being of a size to enter the enlarged end portion of said opening through said die.

In testimony whereof I affix my signature.

GUY R. GAUNTT.
